[57] CLAIM

The ornamental design for a golf ball display rack, as shown and described.

DESCRIPTION

FIG. 1 is a top plan view of a golf ball display rack showing my new design;

FIG. 2 is a front elevational view thereof;

FIG. 3 is a left side elevational view thereof; the right side elevational view being a mirror image thereof;

FIG. 4 is a bottom plan view thereof;

FIG. 5 is a rear elevational view thereof; and,

FIG. 6 is a perspective view thereof.

The broken line showing of a hook and ball is shown for illustrative purpose only and forms no part of the claim.
